(57) **CLAIM**

The ornamental design for the track assembly for lights, as shown and described.

DESCRIPTION

FIG. 1 is perspective top side view of the track assembly for lights of the present invention.

FIG. 2 is a detail view of a portion of the track assembly for lights shown within the dashed circle of FIG. 1.

FIG. 3 is a top side view of the track assembly for lights.

FIG. 4 is an enlarged first end view of the track assembly for lights.

FIG. 5 is an enlarged second end view of the track assembly for lights.

FIG. 6 is a right side view of the track assembly for lights.

FIG. 7 is a detailed view of a portion of the track assembly for lights shown within the dashed circle of FIG. 6.

FIG. 8 is a left side view of the track assembly for lights.

FIG. 9 is a detailed view of a portion of the track assembly for lights shown within the dashed circle of FIG. 8.

FIG. 10 is a bottom side view of the track assembly for lights; and,

FIG. 11 is a detailed view of a portion of the track assembly for lights shown within the dashed circle of FIG. 10.
